(57) **CLAIM**

The ornamental design for a rolling utility cart, as shown and described.

DESCRIPTION

FIG. 1 is a front elevational view thereof of a rolling utility cart showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken lines in the figures show portions of the rolling utility cart, which form no part of the claimed design.
